UNITED STATES PATENT OFFICE.

WILLIAM R. PERRIN, OF CHICAGO, ILLINOIS.

DEVICE FOR EJECTING HOGS FROM SCALDING-VATS.

No. 884,608.

Specification of Letters Patent.

Patented April 14, 1908.

Application filed November 2, 1903. Serial No. 179,520.

To all whom it may concern:

Be it known that I, WILLIAM R. PERRIN, a citizen of the United States, residing at Chicago, in the county of Cook and State of Illinois, have invented certain new and useful Improvements in Devices for Ejecting Hogs from Scalding-Vats, of which the following is a specification.

My invention relates generally to appliances employed in the preparation of dressed meats; and has reference more particularly to a mechanism for facilitating the operations employed in cleaning and dressing slaughtered hogs.

As is well known, in the systems extensively in vogue in the large meat-packing establishments, the hogs, after being slaughtered, are thrown into a scalding vat or tank to loosen the bristles and hair preparatory to the succeeding scraping operation, which is usually performed upon a platform or table arranged adjacent to the scalding vat. In view of the rapidity with which the animals are handled, it is desirable to have expedited means for transferring the scalded hogs from the scalding vat to the scraping table; and to this end my invention consists in a mechanical appliance in the nature of an oscillating ejector or "throw-out", which is power-actuated so as to operate continuously, and which effects the quick and uniform transfer of the animals from the scalding tank to the scraping table without liability of injury from scalding or otherwise to the attendants.

My invention, in an approved form, is illustrated in the accompanying drawings, wherein,—

Figure 1 is a perspective view of a scalding tank having my invention applied thereto; and Fig. 2 is a cross-sectional view through the scalding tank, illustrating my improvement in elevation.

Referring to the drawings, 5 designates the usual scalding tank or vat, and 6 the inclined platform onto which the animals are subsequently discharged for the scraping and cleaning operations.

In carrying out my invention I journal across that end of the tank which is adjacent to the scraping table a shaft 7, on which shaft are rigidly mounted a series of parallel arms 8 extending inwardly of the tank, and at their outer ends upwardly curved and connected by a transverse rod or bar 9; the

rigid frame thus formed constituting in effect a skeleton scoop or pan of a size sufficient to successively raise and discharge the animals. On one end of the shaft 7 is a crank-arm 10, by which the skeleton frame is oscillated by power connections, for which purpose I have shown a pitman 11 adjustably connected to the arm 10 through a pin and slot connection 12, and at its upper end pivoted on the face of a disk 13 fast on a shaft 14 mounted in hangers 15 suspended from an overhead beam 16, the shaft 14 being rotated from a power-receiving pulley 17 through such speed-reducing gearing as may be found desirable or necessary; the connections herein shown comprising a pinion 19 fast on the shaft 18 of the pulley 17 engaging a gear 20 on a shaft 21 which carries at its opposite end a sprocket-wheel 22, which drives, through a sprocket-chain 23, a large sprocket-wheel 24 on the shaft 14.

The operation of the apparatus is obvious from the foregoing description, in connection with the illustration, from which it will be seen that the continuous rotation of the disk 13 effects a uniform oscillation of the skeleton frame or scoop connected to the shaft 7 and constituting the ejector; this ejector dipping in the water to a sufficient depth to enable the animal to be floated to a position directly thereabove, whereupon, on the subsequent rise, it scoops up the animal, and by its continued upward and outward movement throws the animal out upon the table 6 in an obvious manner, and is thereafter immediately returned to receiving position in the tank.

From the foregoing it will be seen that my present invention provides a simple, continuously-operated and expeditious device for ejecting the animals from the scalding tank onto the scraping table.

The oscillating scoop is positively actuated in both directions by continuous driving connections, so that a uniform and steady movement is given to the scoop which prevents splashing and consequent danger of injury or scalding.

I claim:

1. The combination with a scalding tank, of a continuously operating hog ejector comprising a skeleton scoop or pan pivotally mounted across one end of said tank, a power driven shaft, and continuous driving connections between said shaft and ejector serving

to actuate the latter positively in both directions of its movement, substantially as described.

2. The combination with a scalding tank, of a hog ejector comprising a skeleton scoop pivotally mounted across one end of said tank, a continuously rotating power-driven shaft mounted above said scoop, a rotary crank member on said shaft, an oscillatory

crank-arm on the pivot-shaft of the scoop, 10 and a pitman connection between said rotary crank member and oscillatory crank-arm, substantially as described.

WILLIAM R. PERRIN
